ROSWELL R. SHIRLEY, OF ROCKFORD, ILLINOIS.

FEED-MANGER.

1,259,790.

Specification of Letters Patent. Patented Mar. 19, 1918.

Application filed April 21, 1917. Serial No. 163,666.

To all whom it may concern:

Be it known that I, ROSWELL R. SHIRLEY, a citizen of the United States, residing at Rockford, in the county of Winnebago and 5 State of Illinois, have invented certain new and useful Improvements in Feed-Mangers, of which the following is a specification.

This invention pertains to feed mangers especially adapted for feeding horses and 10 cattle, and has more particular reference to mangers adapted to be tilted for the purpose of emptying or delivering accumulated feed or refuse from the manger so that it may be easily kept in a sanitary condition.

15 In this invention I have aimed, primarily to provide a feed manger of the character described, generally improved in construction, especially with respect to maintaining cleanliness of the manger. I have further 20 aimed to provide a substantial and thoroughly practical feed manger of such novel construction as will not only better serve the desired requirements in usage but will permit of manufacturing the manger at a 25 comparatively low cost.

In furtherance of these general objects, I have provided a manger body and a supporting frame therefor of improved construction, enabling but few parts to be employed in a most advantageous manner. The 30 special features in the construction of the manger body and of the frame therefor and in the manner of tiltingly supporting the manger body will all be fully described 35 in the following specification.

In the accompanying drawing,

Figure 1 is a perspective view, partly in section, of a feed manger embodying my improvements;

40 Fig. 2 is a cross-sectional view through the feed manger and shows in dotted lines the manger body swung to a tilted position;

Fig. 3 is a top view of the manger; and

45 Fig. 4 is an enlarged detail sectional view taken substantially on the line 4—4 of Fig. 3.

My improvements are characterized, generally speaking, by the provision of a manger body or feed receptacle having an open top of general rectangular shape and 50 having downwardly converging front and rear walls so that the feed will be easily accessible and the refuse may be completely emptied when the body is tilted for that purpose. A sectional frame supports the 55 manger body in such novel manner that the same may be tilted to an emptying position

and will be limited in such movement by contact of one of the frame parts against the other. The particular construction and the resultant advantages of the manger body 60 and supporting frame will now be described.

The front, back and bottom of the manger body are formed from a single piece of sheet metal designated by character 5, defining the depth and width of the body and being 65 turned downwardly at its front and rear edges 6 and 7 respectively, both for the purpose of reinforcing these edges and to embrace a body member which joins the front and rear sides of the body across the ends 70 thereof. This member, preferably of comparatively light strap iron, is shaped and arranged so that its medial portion 8 extends along and beneath the entire length of the back edge 7 and is bent forwardly, 75 providing side portions 9 and is thence bent inwardly at its ends 11, which project only a short distance into the reinforcing front edge 6 of the manger body. End pieces 12 are secured to the inner sides of the body 80 member 9 and are provided with flanged edges 13 secured to the main body part 5. In assembling the parts thus far described, the ends 12 are first spot welded or otherwise suitably secured along the upper edges 85 to the sides 9 of the strap iron piece and then the latter is placed in position on the main body piece, that is, engaged beneath the downturned front and rear edges thereof, thus positioning and holding the 90 end pieces 12 in coöperating relation to the main body piece. The downturned edges 6 are provided, as shown in Fig. 1, with projections 14 which are now turned inwardly so as to temporarily hold the parts 95 in this relation until they are welded or otherwise secured together. It is preferred to weld the body portion along the flanges 13 and along the strap iron piece so as to constitute the body part a practical integral 100 construction.

For the purpose of bracing the manger body intermediate its front and rear sides and for dividing the manger lengthwise by divisional stays as is desired in mangers of 105 this type, I employ rods 15 which are secured in position in a novel manner. These rods are cut to a length greater than the distance between the walls at the point they are located in the manger body, and are 110 adapted to be inserted at their ends into the sockets 16 formed in the front and rear body

walls. These body walls of sheet metal or some similar resilient material, may be yieldingly flexed outwardly so that the rods may be entered at their ends in the opposed sockets 16, whereupon the sides will spring back to position and confine the rods in the sockets. Additional means employed to positively secure the rods in connection with the body preferably consists of washers or similar pieces 17 placed on the rods 15 before they are inserted, the washers being spot welded to the sides of the manger body so as to permanently secure the rods 15 against displacement.

15 The frame which pivotally supports the manger body serves also to reinforce the same and protect it from injury. To serve these functions, I construct the frame of substantial and heavy material, and the manger body I construct of comparatively light though serviceable material so that the body may be produced at a comparatively low cost. It is preferred that the frame shall border the top edge of the manger body, and in order that the latter may be strengthened and also be capable of being tilted to an unobstructed emptying position, I have provided a sectional frame, one section of which is rigidly secured to the front upper edge of the manger body and is pivotally connected at its ends to the frame at the ends of the manger body, so that the same may tilt on these pivotal connections. The stationary part of the frame is preferably formed of comparatively heavy strap iron, the central portion 18 of which extends lengthwise of the manger body at the rear side thereof and is shaped to provide forwardly projecting arms 19 spaced laterally beyond the body parts 9 and terminating in forward ends 21 turned inwardly adjacent to the front of the body into engagement with the parts 9. The other sectional member is in the form of a similar heavy strap iron 22 adapted to be rigidly secured to the front edge of the manger body in a manner to be presently described and having its ends 23 projected beyond the ends of the manger body and turned rearwardly into juxtaposition with the forward ends 21 of the other frame part in the manner shown. A pivot pin 24 passed through each end of the feed manger and through the ends 21 and 23 of the frame parts pivotally connects these parts together, so that the manger body may be tilted on the pivot pins. A simple and effective way of securing the bar 22 to the manger body is to rivet these parts together in the following manner: The front edges 6 of the manger body are cut away at 25 and rivets 26 are passed through the ends 11 of the strap iron body part before the same is associated with the main body part so that when the body parts are secured together in the manner described above, the rivets 26 are projected forwardly from the

body and will be held against displacement in any direction as will be obvious by an inspection of Fig. 4. Thus, the frame part 22 may be properly drilled and placed in connection with the body so that the rivets 70 project through the drilled holes, and the projected ends may be flattened so as to fixedly secure the parts together.

The frame part 19 may be secured to a wall or any stationary support in any suitable manner. Since it is often desired to mount the manger in the corner of a stall or pen, the back 18 and one side 19 of this frame section are positioned against the corner walls of the stall and bolted or otherwise secured thereto and a bracket (not shown) is employed to connect the opposite side 19 to the wall, the bolts passing through the holes 27 in the side 19. It should be understood, however, that the sides of the 85 frame might be supported in a stationary position by any suitable means.

In use, the manger body occupies a horizontal position, such as shown in Fig. 1, and is held against tilting or swinging downwardly from this position by means of suitable stops between the manger body and the stationary frame. These stops may be formed by shaping the body pieces 9 to provide lateral projections 28 adapted to rest upon seats 29 which are in the form of angle brackets secured to the inner sides of the frame sides 19. When it is desired to empty or deliver any feed or refuse from the manger body, it will be swung upwardly from its back end on the pivotal connections 21 to the position indicated in dotted lines in Fig. 2. By reason of the peculiar manner in which the manger body is supported, it will be noted that there is no obstruction whatsoever to the discharge or delivery of the contents from the manger body. Thus, it is possible to keep the manger clean without any difficulty. It will also be noted that the tilting movement of the manger body will be limited in a very effective manner. This is accomplished by the peculiar shape of the frame parts, so that when the manger body is swung to the tilted position mentioned the under edge of the part 22 at its ends will 115 abut against the underside of the ends 21. A stop of this character is very serviceable and practical, since it will be remembered that the manger body is often forcibly tilted forwardly to dislodge the refuse, and unless a very substantial stop were provided it would be sheered off or injured.

Since feed mangers of this character are generally subjected to severe usage and handling and are often exposed to all weather 125 conditions and because it is desirable to maintain the manger in as sanitary a condition as possible, I have found that by galvanizing the entire structure it will be kept in good serviceable condition for a long time. 130

While there is nothing particularly novel about galvanizing devices of this kind, attention is called to this fact simply so that the importance of certain structural features 5 might be more readily appreciated. It will be evident that if the feed manger were galvanized as a whole the pivotal connections would become so filled with the galvanizing material as to practically prevent tilting of 10 the manger body. For this reason, the manger body and the stationary frame structure are galvanized separately and assembled afterward, the assembling being accomplished simply by inserting the pivot pins 24 15 and slightly flattening their ends to hold them in position. In this connection it will also be noted that the parts through which the pivot pins pass may be drilled at the time they are being formed and may be assembled 20 without trouble, as there is little occasion or practically little possibility of the holes not alining. It will also be noted that both sectional frame parts and the body strap iron parts are simply cut to length and 25 bent to the desired shape and properly drilled, thus avoiding special connections and joining of ends together, and consequently, materially enabling production of my feed manger at a low cost. It will be 30 evident, therefore, considering the simple manner in which the manger body is constructed and assembled as described above and considering also the advantageous features in connection with the mounting and 35 supporting of the manger body, that my improved feed manger may be produced at a comparatively low cost. Furthermore, the parts are so designed that maximum strength and durability is obtained as a result of the 40 special design and arrangement.

It should be understood that while I have illustrated one working embodiment of my improvements, various changes in the construction and arrangement of parts might be 45 made without departing from the spirit and scope of my invention as expressed in the appended claims:

I claim:

1. A feed manger, comprising a manger body, means for supporting the same including a supporting member at each end of the manger, parts fixed to the manger body and projecting beyond the ends thereof into juxtaposition to the outer sides of said supporting members, and means pivotally connecting together said supporting members, said parts and the ends of the manger body so that the latter may tilt on the pivotal connections to an emptying position and will 50 be limited in such movement by contact between said parts and supporting members.

2. A feed manger or the like comprising a manger body, a sectional supporting frame therefor bordering the body, a part of said 55 frame being stationary and a part being

fixed to the manger body along its front edge and extended beyond the ends of the manger and pivotally connected to the stationary part, the extended portions of the frame part being arranged to abut against 70 the underside of the stationary part when the manger body is tilted on said pivotal connections to thereby limit such tilting movement.

3. A feed manger or the like comprising 75 a supporting frame having side bars spaced apart horizontally, a manger body interposed between said side bars, and means secured to the front portion of the manger body and extending around the side bars to 80 the outer sides thereof and pivotally secured thereto so as to pivotally mount the manger body on the side bars, said means and the side bars being so relatively arranged that the means will abut against the 85 undersides of said arms when the manger body has been tilted to an upright position to thereby limit the movement of the manger body in this position.

4. A feed manger comprising a manger 90 body, stationary side bars located adjacent to each end of the manger body, a pivotal connection between said side bars and the ends of the manger body whereby the latter may be swung on said pivots from a 95 horizontally disposed to an upright position in which material may be delivered from the manger body, and means carried by the manger body and arranged to abut against the underside of one of said side 100 bars when the manger body has been swung to upright position for limiting movement of said body to such position.

5. A feed manger comprising a manger body, fixed supports at each side of the 105 body spaced laterally therefrom and having front ends extending inwardly into proximity to the sides of the manger body, said body being equipped at opposite ends with outwardly projecting fixed parts associated with the outer sides of said front ends of the supports, and pivotal connections between said parts, end supports and manger body whereby the latter may be 110 tilted forwardly on the pivotal connections and will be limited in such movement by contact between said fixed parts and end supports.

6. A feed manger comprising a manger body, means for supporting the body comprising a pair of U-shaped frame members adapted to border the manger body, one of said frame members being adapted to serve as a stationary support with its spaced arms extending horizontally, the other member having its medial portion fixed to the front portion of the manger body and being arranged with its arms in juxtaposition to the outer sides of the arms of the first frame member, and a pivotal connection between 115 120 125 130

the arms of said frame members and the adjacent sides of the manger body whereby the latter is supported so as to be capable of tilting on said pivotal connections to an emptying position and also whereby the arms of the second frame member will abut against the underside of the arms of the first frame member.

7. A feed manger comprising a manger body having an open top of general rectangular shape, and means for supporting the manger body comprising a frame bordering the sides and back of the body and adapted to be rigidly secured to a fixed support, a member secured to the body along its front side and having its ends projecting beyond the ends of the body and associated with the forward ends of the side frame parts, at the outer sides thereof, and means pivotally connecting together the ends of the front frame member, the forward ends of the side frame parts and the manger body adjacent to the front of the manger body so that the latter may tilt upwardly from its rear side to empty forwardly and will be limited in such tilting movement by contact between the side frame parts and extended ends of the front frame member.

8. In a feed manger, a manger body having resilient sheet metal side walls, spaced rods adapted to extend intermediate and to be supported by said walls, the walls having sockets on their inner sides for the reception of the ends of said rods the rods being

of such length that the side walls must be 35 yieldingly flexed outwardly to receive the rods in the sockets, and washers or the like mounted on the rods and being fixed to the walls to insure against displacement of the rods from the sockets.

9. A feed manger having a body comprising a main body portion formed of sheet metal providing the front, back and bottom of the manger body, the front and back edges of which are turned downwardly, a strap iron bar or the like having its medial portion engaged beneath the said down-turned edge at the rear of the main body portion and having its end portions bent forwardly and thence inwardly within the 50 downturned portions at the front of the main body portion, a rivet passed through each inwardly turned end of said bar and arranged with its head intermediate the bar and the adjacent wall of the main body 55 member and with its shank projecting forwardly through an opening in the down-turned edge of the main body portion, stationary frame bars disposed adjacent to each end of the manger body, and a bar extending along the front end of the manger body, and being secured thereto through the agency of said rivets and having rearwardly turned ends associated with said side bars, and means pivotally securing the ends of 60 the front bar to the side bars.

ROSWELL R. SHIRLEY.
